UNITED STATES PATENT OFFICE.

ARTHUR M. SMITH, OF SAN FRANCISCO, CALIFORNIA, ASSIGNOR TO MARSHALL & STEARNS COMPANY, OF SAN FRANCISCO, CALIFORNIA, A CORPORATION OF CALIFORNIA.

PORTABLE FOLDING BED.

Application filed September 10, 1924. Serial No. 736,872.

This invention relates to portable folding beds of the type mounted on a carriage frame adapted to be up-ended thereon so as to be moved about from place to place within a room and stored in narrow closet spaces.

It is desirable in such beds to provide counter-balancing springs to assist in the raising of the bed to folded position, but in employing counter-balancing springs there is a tendency for the carriage frame of the bed to flop or fold over on the bed frame when the latter is extended, and the springs are under heavy tension, for the reason that the carriage frame is merely mounted on rollers, and is not anchored as in the case of wall-beds. This tendency for the carriage frame to tip is also accentuated by reason of the fact that the base of the carriage frame must be kept within narrow limits, to permit of its being stored in small spaces.

The object of the present invention is to provide simple and inexpensive means for preventing the carriage frame from flopping over on to the bed frame when the bed is extended and the counter-balancing springs are under tension. A further object is to provide extensible means for this purpose, and to control the action of the same, so that when the bed frame is extended said means will be automatically extended into position to brace or support the carriage frame against tilting movement, and when the bed frame is folded said means will automatically be retracted into compact folding position against the carriage frame.

This object I accomplish by the provision of laterally swinging supports or braces so connected with the bed frame that when the latter is lowered or extended the braces or supports are automatically swung out to position beneath the bed frame and the front of the carriage frame, and in engagement with the floor, and when the bed frame is folded said swinging supports are automatically moved into folded position adjacent the carriage frame so as to allow the latter to be moved into narrow spaces such as a closet or receptacle.

One form which my invention may assume is exemplified in the following description and illustrated in the accompanying drawings, in which

Fig. 1 shows a perspective view of a bed in extended position and equipped with

mechanism in accordance with my invention;

Fig. 2 shows a plan view in section of the head portion of the bed, illustrating the means for controlling the swinging movement of one of the braces;

Fig. 3 shows a perspective view of the connections between the folding bed frame and one of said braces or supports;

Fig. 4 shows a perspective view of the bed shown in Fig. 1, with the bed frame in raised position;

Fig. 5 shows a view similar to Fig. 2, with the brace or support in extended position;

Fig. 6 shows a detail view of the head portion of the bed in elevation, illustrating one of the swinging braces or supports in folded position.

The folding bed of the present invention comprises a carriage frame which consists preferably of an upright headpiece 8, side rails 9, and a front bar 10, forming a substantially rectangular frame in plan, mounted upon rollers or casters 11. Pivotally mounted upon the side rails 9 is a bed frame 12 carrying at its outer end the usual folding foot-piece 13. This bed frame is counter-balanced by means of contractible helical springs 14 extending from a cross-bar 15 on the bed frame to the front bar 10 of the carriage frame.

It will be seen that when the bed frame is lowered or extended as illustrated in Fig. 1, there is a tendency for the carriage frame to flop forwardly, due to the action of the springs 14 under tension, the short or narrow wheel base of the said carriage frame being insufficient to prevent such tilting of the said carriage frame. To overcome this tilting or flopping of the carriage frame I provide an extensible brace or support 16 at each side of the carriage frame and in front thereof. Each brace or support is pivotally connected on a vertically disposed axis to the front of one of the side rails 9, so as to swing horizontally or nearly so. The "toe" or outer end of each brace or support is provided with a caster or roller 17 for contact with the floor when the brace or support is extended in a position to align with the side rails 9. These braces or supports are adapted to be folded in a position parallel with the front rail 10 of the carriage frame, and their pivots are preferably arranged at a slight inclination, so that when

105

110

the said braces are in folded position their casters or rollers 17 will be slightly raised above the floor, as indicated in Fig. 6, so as not to interfere with the transporting of the carriage frame.

The movement of these braces or supports from tilted to extended position, and vice versa, is entirely automatic, and controlled by the raising and lowering of the bed frame. The operating connections for this purpose include a lever 18 for each brace or support fulcrumed at 19 upon the lower portion of the carriage frame. Each lever at its outer end is connected with a link 20, 10 which in turn connects with the adjacent brace or support. The opposite ends of both levers 18 are connected together by a contractible helical spring 21 acting to pull both levers into position where the braces 15 or supports are extended. There is an up-standing lug 22 on each lever, so positioned as to be engaged by the end-rail at the head of the bed frame when the latter is being moved into closed or folded position. This 20 end-rail, as indicated in Fig. 4, strikes the upstanding lug 22 and causes the levers 18 to be swung into the position shown in Fig. 2, where the legs or braces 16 will be folded in front of the carriage frame.

25 From the foregoing it will be seen that I have provided a simple and inexpensive mechanism for bracing and supporting a carriage frame against forward tilting movement when the bed frame is extended, and the counter-balancing springs are under tension. These braces or supports are positioned beneath the bed frame, and are automatically controlled so as to be folded when the bed frame is in closed position.

30 By the present arrangement I am enabled

to counter-balance the bed frame with counter-balancing springs, thus dispensing with the weights generally employed heretofore for counter-balancing portable beds of this character.

45 Various changes in the construction and arrangement of the several parts herein shown and described may be employed without departing from the spirit of my invention as disclosed in the appended claim.

50 What I claim as new and desire to secure by Letters Patent is:

55 In a portable folding bed having a carriage frame of substantially rectangular outline, an up-ending bed pivotally mounted on the carriage frame, counter-balancing springs connected to the head of the bed frame and to the forward portion of the carriage frame near the bottom of the latter for assisting in raising the bed frame, a laterally swinging brace pivoted to the front portion of the carriage frame at each side thereof, and provided with a caster at its outer end for contact with the floor, and means controlled by the raising and lowering 60 of the bed frame, to cause said braces to be moved into extended position in front of the carriage frame when the bed frame is lowered, and to be swung into folded position adjacent the carriage frame when the 65 bed frame is raised, said control means including a lever for each brace, springs connecting said levers together and serving to swing said braces into extended position, and means on each lever for contact with the 70 head end of the bed frame to move said levers to position where the said braces will be retracted.

75 ARTHUR M. SMITH.
